2 SHEETS-SHEET 2.

UNITED STATES PATENT OFFICE.

ROY KELLEY, OF MINDEN CITY, MICHIGAN.

IGNITER TRIP DEVICE FOR EXPLOSION-ENGINES.

1,093,191.

Specification of Letters Patent. Patented Apr. 14, 1914.

Application filed August 13, 1913. Serial No. 784,605.

To all whom it may concern:

Be it known that I, ROY KELLEY, a citizen of the United States, residing at Minden City, in the county of Sanilac and State of Michigan, have invented certain new and useful Improvements in Igniter Trip Devices for Explosion-Engines, of which the following is a specification.

This invention relates to improvements in actuating or trip devices for the igniters of explosion engines, and one of the main objects of my invention is to provide an actuating or trip device which may be readily adjusted during the operation of the engine to either retard or advance the spark, both for the purpose of facilitating the starting and regulating the engine during operation.

The invention has other novel features which will be more fully described in connection with the accompanying drawings and which will be more particularly pointed out in and by the appended claims.

In the drawings: Figure 1, is a view in side elevation of a portion of the explosion engine provided with an igniter and showing the application of one form of the device of the invention thereto. Fig. 2, is a perspective detached view of one of the operative parts of my improved device. Fig. 3, is an end view of the actuating or trip device with one portion in section. Fig. 4, is a vertical, longitudinal, sectional view of the device shown in Fig. 3, with certain parts in elevation. Fig. 5, is a detail end view of one part of the device detached from the remainder thereof.

Like characters of reference designate similar parts throughout the different figures of the drawings.

As illustrated, the device of my invention is applied to an explosive engine 1, having an igniter device 2, provided with a spring controlled operating or trip lever 3. A push or cam rod 4, is reciprocably mounted in bearings, one of which is indicated at 5', and it will be understood that the push rod may be actuated from the crank shaft by any of the approved means.

Adjustably mounted upon the push rod 4, is a support which may be in the form of a bracket 5, having adjustable means in the form of screws 6, for locking the bracket in any desired position of adjustment in the push rod 4. I movably mount a trip rod support 7, preferably by means of a pivot 8, on the bracket 5, as clearly shown in Fig.

4. In this construction the upper end of the bracket projects into a recess 9, formed in the support 7. The front wall 10, of said recess is normally in spaced engagement with the front face of the bracket so as to permit of a downward rocking action of the support 7, from the normal position shown, in the direction of the arrow a. I preferably provide a spring 12, for holding the support 7, in a normal position, and one end of the spring 12, is shown connected with a bracket arm 13, and the other end with a support arm 14.

The support 7, is preferably in the form of an elongated body having a longitudinally disposed bore, the forward portion 15, of which is smooth and preferably cylindrical, while the rearward portion 16, thereof, is threaded. In the threaded portion 16, I provide adjustable stop means which may be in the form of a threaded rod 17, having an operating thumb nut 18. A suitable lock or set may be provided in the form of a thumb nut 19, which is threaded on the rod 17, and is adapted to be turned into engagement with the rear end of the body 7, to lock the rod 17, in its adjusted positions.

A trip rod is longitudinally movable in the support 7, and in the construction shown, the rod has a cylindrical rear portion 20, which fits the cylindrical portion 15, of the bore with a slight working clearance so as to be rotatably and longitudinally movable therein. The forward end 21, of the bar is 85 preferably polygonal in cross section, and in the present construction the same is shown rectangular, as indicated in Figs. 3 and 5. The forward end of the trip rod 21, is adapted for engagement with the lever 3, 90 and is provided with four engaging portions indicated at 22, 23, 24, and 25.

It is one of the features of my invention to not only provide for accuracy of the trip operation of the lever 3, but also to provide 100 for the adjustment of the trip rod so that when one of the engaging end portions becomes worn, the trip rod can be shifted or adjusted so as to bring a new engaging portion into operative proximity with the lever 3. When all of the operating portions have become worn, then the end can be ground flat so as to again present four sharp edges for operating the lever 3.

Referring to the specific means for adjusting the trip rod to hold any one of its engaging portions in proximity to the lever.

3, it will be seen that a shoulder will be provided at the juncture of the cylindrical and square portions 15 and 21, respectively, of the trip rod, and I fix to the cylindrical portion 20, a perforated element 26, which is shown as provided with openings 27, 28, 29, and 30, one for each of the actuating portions 22 to 25, inclusive. On the support 7, I mount a rod 31, adapted to slidably engage any one of the openings 27 to 30, which may be adjusted into registry therewith.

It will readily be seen from the foregoing description that while the trip rod may move longitudinally in the bore 15, it will be held against rotative movement so as to maintain one of the operating portions in a position to operate the trip 3. This construction will permit the adjusting rod 17, to be turned so as to advance the trip rod in the support 20, 7, or turned so as to permit the trip rod to be retracted.

I provide means for holding the trip rod in engagement with the end of the rod 17, irrespective of the adjustment of the latter. 25 As shown, such means consists of a rod 32, which is cranked at 33, to fit over the square portion 21, of the trip rod. The ends of the rod 32, are connected with springs 34, so as to engage studs 32' with opposite openings 30 in the element 26, and always hold the trip rod retracted against the end of the stop 17. The springs 34, are connected at 35 to the reduced ends of pivot 8 in a manner to be normally under tension, and in a manner to be 35 inclined downwardly from the horizontal so as to always hold the rod 32, in place.

It will be readily seen from the foregoing description that on to and fro, or reciprocating movement of the push rod 4, the trip rod 40 will engage the trip lever 3, and actuate the same, and the support 7, will be rocked from a normal position in the direction of the arrow *a*, while the end 21, is released from the lever 3. The spring 12, will return 45 the support 7, to a normal position after the trip rod has been released from the lever 3.

If it is desired to advance the spark, the rod 17, will be adjusted so as to advance the trip rod outwardly in the bore 15, so as to 50 cause an earlier engagement with the lever 3. If it is desired to retard the spark, the rod 17, will be adjusted to permit retraction by the springs 35, of the trip rod in the bore 15, so as to provide for a later engagement 55 with the lever 3. The adjustment shown is the maximum retraction adjustment for a maximum retard of the spark.

It will be readily seen that the device of my invention provides for adjustment during the operation of the engine so as to avoid the troublesome operation of stopping to change the timing of the igniter actuating device.

In starting the engine, the spark can be 60 retarded so as to permit of turning the en-

gine over slowly until a proper ignition and explosion occurs so as to start the same, thus avoiding any kicking or backward turning of the crank shaft. Where the spark is permanently or in any way advanced so that it can not be retarded when the engine is started, great danger is encountered in cranking the engine, and it requires a considerable amount of effort.

In accordance with my improved construction, the spark can be retarded or advanced during the starting operation, and it can also be adjusted as desired after the operation has been effective and while the engine is running.

While I have herein shown and described one specific form of my invention, I do not wish to be limited thereto except for such limitations as the claims may import.

I claim:

1. In an internal combustion engine, a push rod, a trip bracket adjustably mounted on said rod, an igniter trip rod support pivoted on said bracket to rock from a normal position in one direction, a spring for holding said support in a normal position, a trip rod rotatably and longitudinally movable in said support, a perforated element fixed on said trip rod, a rod fixed on said support and slidably in one of the perforations of said element to hold the trip rod against rotation, an adjustable stop for limiting the movement of the trip rod in said support in one direction, and spring means engaging said perforated element to hold said trip rod in engagement with said adjustable stop, substantially as described.

2. In an internal combustion engine, a reciprocating rod, a trip bracket adjustably mounted on said rod, an igniter trip rod support on said bracket, an igniter trip rod longitudinally movable in said support, an adjustable stop for permitting said trip rod to advance, or retard, the sparking, spring means for holding said trip rod against said stop, and slidable means for preventing rotation of said trip rod, substantially as described.

3. In an internal combustion engine, an igniter device, a trip rod having a plurality of independent portions for engaging said device to actuate the same, and means for holding said trip rod in any one of several positions to dispose any one of said portions in engaging proximity to said device.

4. In an internal combustion engine, an igniter device, an element having a plurality of portions for engaging said device, and means slidably connected with said element for holding the same in any one of a number of pre-determined positions to maintain one of said engaging portions in operative proximity to said device, substantially as described.

5. In an internal combustion engine, an

igniter device, a longitudinally movable trip rod for actuating said device and provided with a plurality of independent actuating portions, means rotatably supporting said trip rod and mechanism having slidable engagement with said trip rod, for holding the same in any one of selected positions to dispose selected engaging portions in operative proximity to said device and maintain said trip rod in such selected position, substantially as described.

6. In an internal combustion engine, an igniter device, a trip rod support having a bore provided with a smooth and a threaded portion, a threaded rod in the threaded por-

tion of said bore, a trip rod in the smooth bore portion, and adapted for engagement with said device, means for locking the threaded rod in adjusted positions to advance or retract the trip rod, means engaging the trip rod to hold same in engagement with said threaded rod, and means slidably engaging the trip rod to hold same against rotation, substantially as described. 20

In testimony whereof I affix my signature 25
in presence of two witnesses.

ROY KELLEY.
